UNITED STATES PATENT OFFICE.

ARTHUR N. AMES, OF FRANKLIN FALLS, NEW HAMPSHIRE.

CIRCULAR-KNITTING MACHINE.

962,292.

Specification of Letters Patent. Patented June 21, 1910.

Application filed March 12, 1906. Serial No. 305,707.

To all whom it may concern:

Be it known that I, ARTHUR N. AMES, a citizen of the United States, residing in Franklin Falls, in the county of Merrimack 5 and State of New Hampshire, have invented an Improvement in Circular-Knitting Machines, of which the following description, in connection with the accompanying drawings, is a specification, like letters on the 10 drawings representing like parts.

The present invention relates to a circular knitting machine, and is embodied in a machine of that type known as the full automatic, in which the machine, once started, 15 will knit a stocking complete; the transfer from the circular knitting for the leg and foot to the reciprocating knitting for the heel and toe, and vice versa, being accomplished by automatic pattern mechanism; 20 and the machine being stopped automatically when the stocking has been completed.

The invention is mainly embodied in a novel pattern mechanism to coöperate with a thread shifting device for striping around the 25 leg and foot, the object being to utilize a pattern chain comparatively short in length, the said chain being controlled by a main pattern mechanism which stops the movement of the chain except when it is in active operation for controlling narrow stripes, so that 30 it is unnecessary to use a very long chain in case there are groups of narrow stripes some distance apart in the pattern for a long stocking.

35 Figure 1 is a front elevation of a sufficient portion of a knitting machine to include the features which embody the invention; Fig. 2 is a top plan view partly in section; Fig. 3 is a side elevation, partly in section, looking toward the right hand side of Fig. 1; Fig. 4 is a detail on a larger scale showing 40 the pattern chain and its coöperating parts; Fig. 5 is a vertical section on line α^5 of Fig. 4; and Fig. 6 is a horizontal section on line 45 α^6 of Fig. 4.

The driving mechanism of the machine is substantially like that employed in machines of this type as heretofore constructed, as shown, for example, in Letters Patent No. 50 745,449, to Mayo, Dec. 1, 1903, the main shaft A, Fig. 1, having sleeved thereon a driving pulley A^2 and a loose pulley A^3 , the driving pulley having connected therewith a driving gear A^4 which meshes with a large 55 gear A^5 which is driven continually when

the belt is on the pulley A^2 . The said large gear A^5 is connected by means of a pitman A^6 with a gear segment A^7 upon a rock-shaft A^8 , which, through the action of said pitman A^6 , is oscillated continuously during 60 the operation of the machine. The said gear segment is in mesh with a gear A^{10} sleeved on the shaft A, and free to oscillate thereon, the said gear A^{10} , therefore, being oscillated so long as the machine is in operation. 65

Interposed between the driving gear A^4 and the oscillated gear A^{10} is a clutch member B, which is shown as a sleeve splined on the shaft A so as to be connected therewith, so far as relates to rotating or oscillating motion, the said clutch member B having projections B^2 and B^3 which are adapted to engage respectively with shoulders in the gears A^4 and A^{10} . When, therefore, the clutch member B is in engagement with the gear A^4 , as shown, the shaft A will be rotated, while if the clutch member B is shifted to the other position so that the said clutch member is connected with the gear A^{10} the shaft will be oscillated. The 70 said shaft A is further provided with a gear A^{12} , which is in mesh with a gear C on a stub shaft C^2 which is also provided with a bevel gear portion C^3 intermeshing with a bevel gear C^4 on a portion of the cam cylinder C^5 , so that the said cam cylinder is rotated or oscillated in accordance with the 75 operation of the shaft A, the rotary movement of the cylinder performing the circular knitting operation, while the oscillating movement thereof performs the reciprocating knitting operation by which the heel and toe of the stocking are formed, substantially as in the patent to Mayo above 80 cited.

The starting and stopping of the machine, and the shifting from the circular to the oscillating movement of the cam cylinder are controlled by a pattern-wheel D, the 85 specific construction and operation of which need not be herein described, since they do not enter into the novel features of the present invention. The said pattern wheel is controlled in the usual way by the fast and loose gears D^2 and D^3 (Figs. 2 and 3) which have mutilated portions and which are rotated through the agency of a small gear D^4 operated from the oscillated shaft A^8 by a pawl D^5 and ratchet D^6 . The 90 95 100 105 110

struction is substantially like that shown in Letters Patent No. 474,671, W. H. and G. D. Mayo, May 10, 1892.

In knitting stockings having stripes extending around the leg, threads of different colors are employed and alternately thrown into and out of the path of the needles by means of shifting thread guides, the construction and operation of which, as herein shown, are already known to the art. Briefly, these thread guides may be described as consisting of guide members E, (Figs. 2 and 3) which are carried by the rotating cam cylinder C⁵, each guide member being pivotally supported at E² and having a projection E³ which is arranged to be acted on by an upright projection from a slide E⁴ to tip the guide into or out of the path of the needles. The slides E⁴ are on different levels, as best shown in Fig. 1, and project forward into the path of a cam or cams E⁵. In the construction shown there are two cams E⁵ and these cams are vertically movable in accordance with the operation of the special pattern mechanism under consideration so as to engage one or the other of the slides E⁴, as controlled by the pattern, so as to shift the thread guides with relation to the needles. The two slides E⁴ are provided with a cross-connection E⁶, herein shown (Fig. 2) as an arm pivoted between them and connected at opposite sides with the slides respectively, so that the movement of either slide produces a corresponding movement of the other in the opposite direction. The purpose of using two cams is merely to lessen the distance necessary to move the cam member. The cams E⁵ are shown as supported by means of guide pins E⁷ (Figs. 1 and 3) one of the said pins being in engagement with a lever a (Fig. 1) pivoted on a portion of the frame and connected by means of a link a² with a controlling lever a³ pivoted at a⁴, and directly operated by the pattern chain a⁵ which is provided with a series of projections a⁶ properly spaced in accordance with the pattern desired. Each time, therefore, assuming that the chain a⁵ is traveling, one of the projections a⁶ comes under the end of the lever a³, as shown in Fig. 4, the link a² will be pulled downward and will act through the lever a to raise the cam portion and shift the thread guides. After the projection a⁶ has passed the end of the lever a³ the reverse takes place. Assuming, therefore, that the chain a⁵ were solely depended upon for the operation of the lever a, and that the pattern called for fine stripes at some distance apart, it is obvious that a very long chain would have to be employed, since the projections a⁶ would have to be spaced a long distance apart, so that the chain might travel during the knitting of a considerable portion of the stocking in one color between the stripes.

It is the purpose of the present invention to obviate the necessity of using a long chain, this being accomplished by causing the chain a⁵ to stop its travel during the knitting of a considerable portion of a stocking in one color between stripes, the starting and stopping of the chain being controlled by a pattern controlling device on some traveling member of the machine, such as the main pattern shaft D⁷.

As herein shown, the chain a⁵ is mounted on a sprocket wheel a⁷ and preferably runs over an idle sprocket a⁸ (Fig. 1) the sprocket wheel a⁷ having a ratchet a⁹ which is operated by a pawl a¹⁰ arranged to be continuously reciprocated during the operation of the machine. The pawl a¹⁰ is pivoted on an arm a¹² (dotted lines, Fig. 4) having a pivotal support and a forked projection a¹³ engaged by a pin a¹⁴ upon an elbow lever a¹⁵, one end of which is provided with a cam roll a¹⁶ engaged by a cam surface formed on the face of a disk C⁶ which is mounted on the shaft C² which carries the gear C. The cam-roll a¹⁶ is held in engagement with the cam by means of a spring a¹⁷ connected with the pawl carrying arm a¹². In order to stop the travel of the chain, however, the pawl a¹⁰ is under the influence of a secondary member a¹⁸ which is shown as a lever pivotally supported at a¹⁹ and normally held in the path of projections a²⁰ (Figs. 3, 5 and 6) upon the pattern chain a⁵, by means of a spring a²¹. This controlling member a¹⁸ is provided with a supporting surface a²² which engages a projection a²⁰ from the pawl a¹⁰, and it has an inclined surface a²³ in the path of the projections a²⁰, so that when in the travel of the pattern chain a⁵ one of the said projections comes in contact with the inclined surface a²³ on the said supporting member a¹⁸, it will lift the said supporting member and carry the pawl a¹⁰ out of engagement with the ratchet teeth. The momentum of the chain, however, carries the projection a²⁰ past the supporting member a¹⁸ before the travel of the chain actually ceases, and it is, therefore, necessary to afford a secondary support for the stop. This secondary support, moreover, may be utilized to control the starting of the chain, as will be described. The said secondary support is shown as consisting of a spring latch b, which is arranged to snap, under the influence of the spring b⁸, in under a shoulder or projection a²⁴ when the member a¹⁸ is lifted, thus holding the same in its lifted position and causing the pawl a¹⁰ to ride back and forth on the supporting surface a²², in response to the operation of the cam surface on the disk C⁶, without producing any feed of the chain. Assuming, therefore, that the pattern calls for two or more narrow stripes close together, the projections a²⁰ upon the pattern chain are arranged to stop the move-

ment of the chain after the proper number of pattern projections a^6 have passed under the lever a^3 and the solid knitting without stripes will then take place as long as is necessary without further movement of the chain.

To set the chain a^5 in operation again the latch b is under the control of engaging projections carried by some part of the machine which travels during the entire knitting operation, the said projections being herein shown as blocks b^2 (Figs. 2 and 3) which are secured in the desired positions to one or both of the fast and loose gears D^2 and D^3 , so as to act at the intervals desired in starting up the pattern chain. These blocks are preferably secured in holes D^{20} in the gears, so that they may be readily adjusted as to position, and are mounted on the adjacent faces of the gears.

The blocks b^2 act upon an arm b^3 which is mounted on the rock shaft b^4 , and which projects between the gears D^2 and D^3 , as best shown in Fig. 2, so as to coöperate with the blocks b^2 on either gear which is in operation. The rock shaft b^4 is connected with an arm b^5 , which in turn is connected by means of a link b^6 with an arm or elbow b^7 (Figs. 3 and 5) forming a part of the latch b , so that each time one of the projections b^2 comes in contact with the arm b^3 , the latch b will be moved out of engagement with the pawl supporting member a^{18} , permitting the same to drop and thus letting the pawl a^{10} come into engagement with the ratchet teeth a^9 to start the feed movement of the chain. Assuming, for example, that in a long stocking the pattern calls for three narrow stripes followed by a considerable length of solid color, the pattern can be so arranged that one of the projections a^{20} will reach the pawl supporting member a^{18} after three of the projections a^6 on the pattern chain a^5 have acted, thus stopping the pattern chain. The plain knitting will then continue to such a position as may be determined by the posi-

tion of the next projection b^2 , which will start the chain a^5 , repeating stripes as before. By these means a long stocking having a number of stripes can be knit with a comparatively short pattern chain, which would otherwise be impossible unless all the stripes are equi-distant from each other, and close together, since if the fine stripes were widely separated a continuously traveling chain would have to have the pattern controlling projections separated a distance equivalent to that between the sets of narrow stripes.

Claims.

1. In a knitting machine, a plurality of thread-guides; a pattern chain for shifting said thread-guides; a ratchet to produce a movement of said pattern-chain; a pawl co-operating with said ratchet; a movable support for said pawl to hold it out of the path of said ratchet; devices connected with the pattern-chain to move said support; an automatic retaining device for said support; a main pattern controlling mechanism; and means connected with said mechanism for tripping said retaining device.

2. In a knitting machine, a plurality of thread-guides; a pattern chain for shifting said thread-guides; a ratchet to produce a movement of said pattern-chain; a pawl co-operating with said ratchet; a movable support for said pawl to hold it out of the path of said ratchet; devices connected with the pattern chain to move said support; a spring-latch to hold said support; a lever connected with said spring latch to release it from said support; a separate continuously traveling member; and a series of abutments carried by said member to operate at intervals upon said lever.

In testimony whereof, I have signed my name to this specification in the presence of two subscribing witnesses.

ARTHUR N. AMES.
